UNITED STATES PATENT OFFICE.

LESLIE STEVENS, OF GLEN RIDGE, NEW JERSEY.

DESIGN FOR A SOUND AMPLIFIER.

Application filed August 23, 1924. Serial No. 10,538. Term of patent 7 years.

To all whom it may concern:

Be it known that I, LESLIE STEVENS, a citizen of the United States, residing at Glen Ridge, in the county of Essex and State of New Jersey, have invented a new, original, and ornamental Design for a Sound Amplifier, of which the following description, in connection with the accompanying drawing, is a specification.

Fig. 1 is a front view;

Fig. 2 is a side view; and

Fig. 3 is a top, or plan, view, of a sound amplifier showing my new design.

I claim:

The ornamental design for a sound amplifier as shown.

LESLIE STEVENS.
